UNITED STATES PATENT OFFICE.

DWIGHT H. WAGNER, OF WHEELING, WEST VIRGINIA, ASSIGNOR TO
WHEELING CORRUGATING COMPANY, OF WHEELING, WEST VIR-
GINIA, A CORPORATION OF WEST VIRGINIA.

DESIGN FOR A CENTER PLATE FOR CEILINGS.

SPECIFICATION forming part of Design No. 36,699, dated December 22, 1903.

Application filed November 16, 1903. Serial No. 181,448. Term of patent 7 years.

to all whom it may concern:

Be it known that I, DWIGHT H. WAGNER, a citizen of the United States of America, and a resident of Wheeling, county of Ohio, and 5 State of West Virginia, have invented a certain new, original, and ornamental Design for Center Plates for Ceilings, of which the following is a specification, reference being had to the accompanying drawing, forming part
hereof.

The figure is a plan view of a plate for form-

ing one-half of the center of a ceiling design, showing my new design.

What I claim as new, and desire to secure by Letters Patent, is—

15 The ornamental design for a center plate for ceilings, as herein shown.

DWIGHT H. WAGNER.
